UNITED STATES PATENT OFFICE

ETHAN I. DODDS, OF PULLMAN, ILLINOIS, ASSIGNOR TO THE PULLMAN COMPANY, OF CHICAGO, ILLINOIS, A CORPORATION OF ILLINOIS.

DOOR-OPERATING MECHANISM FOR GONDOLA CARS.

No. 825,020

Specification of Letters Patent.

Patented July 3, 1906.

Application filed April 3, 1905. Serial No. 253,413.

To all whom it may concern:

Be it known that I, ETHAN I. DODDS, a citizen of the United States, residing at Pullman, in the county of Cook and State of Illinois, have invented certain new and useful Improvements in Door-Operating Mechanisms for Gondola Cars, of which the following is a specification.

The object of my invention is to provide an improved door-operating mechanism for cars, particularly those of the gondola type. As is well known, these cars are provided with downwardly-swinging hinged doors constituting unitedly the bottom of the car, and hitherto various devices have been proposed and employed for effecting the return of the doors to closed position after the discharge of the load wherein the doors are released and allowed to open under their own gravity and that of the load.

More particularly my invention aims to provide a door-operating mechanism that is economical to construct, efficient in operation, and readily accessible for repair when it is in any way injured or broken.

To this end my invention consists in a door-operating mechanism for cars of the type referred to having the peculiarities of construction and novel mode of operation substantially as hereinafter described, and more particularly pointed out in the claims.

In the accompanying drawings I have shown so much of a steel gondola car as is essential to the disclosure and clear understanding of my invention.

Referring to the drawings, Figure 1 is a view, partly in end elevation and partly in cross-section, of a car-body equipped with my improved door-operating mechanism. Fig. 2 is a side elevational view of a portion of said car; and Fig. 3 is a top plan view, in horizontal section, through the side and end walls of so much of the car as is shown in Fig. 2.

Referring to the drawings, 1 designates the center sills, which in cars of this type usually accommodate the draw-bar and constitute also the draft-sills.

2 designates the side plates, and 3 the end plates, of the car-body.

4 designates each of a series of doors hinged at their inner edges to the center sills, as shown at 5, and unitedly constituting the discharging-bottom of the car.

6 represents the side stakes, which are preferably made by suitably cutting an I-beam.

obliquely or on the bias, so as to preserve the flange at one side, and a portion of the web tapering in width from top to bottom, so as to bring the widest portion adjacent to the floor, where the greatest strain occurs. Rotatably mounted in the webs of the side stakes 6 is an operating-shaft 7, having a squared end 7^a, to which the operating-arm (not shown) or other actuating means may be applied to turn the same. Fast on the shaft 65 7, opposite each of the doors 4, is an arm 8, the outer end of which has pivotally connected thereto a link 9, having a curved or bent lower end 9^a, (more particularly shown at the left in Fig. 1,) the lower end of which link is 70 connected to the free outer margin of the door 4 by a chain 10.

It will be observed that when the door is closed the arm 8 extends upwardly and the bent portion 9^a of the link 9 rests over the operating-shaft 7 in such a way as to resist the downward pull of the door and hold the latter securely in elevated position. To discharge the load, it is necessary only to rock the shaft 7 to a point where the upper end of the arm 8 80 passes to the opposite side of a vertical line extending through the shaft 7, whereupon the weight of the door and its load causes the door to drop to the position shown in dotted lines at the left of Fig. 1, permitting the ready discharge of the load to one side of the car, in which position the arm 8 and link 9 both hang downwardly from the shaft 7.

I am aware that it is old to operate pivoted doors of cars of this type by means of chains 90 connected to the outer margin of the door and winding about a longitudinally-extending shaft mounted on or adjacent to the side wall of the car. This is objectionable, however, owing to the locking of the links of the 95 chain, that frequently causes the breakage of the latter. In this device it will be observed that the locking effect is produced by the curved end of the link 9 overlying the shaft 7, and the chain is not wound up at all. Obviously the above-described door-operating device can be applied to a car having either a single door or a plurality of doors forming the hinged bottom of the car.

This patent is intended to embrace only so 105 much of the disclosure made herein as is covered by the claims.

I claim—

1. A door-operating mechanism for drop-bottom cars comprising a longitudinally-ex- 110

tending shaft mounted opposite the side wall of the car, a member connected to and adapted to hook over said shaft when the door is raised, and a chain connecting said member with the door, substantially as described.

2. A door-operating mechanism for drop-bottom cars comprising a longitudinally-extending shaft mounted opposite the side wall of the car, a member connected to and adapted to hook over said shaft when the door is raised, and a chain connecting the lower end of said member with the outer margin of the door, substantially as described.

3. A door-operating mechanism for drop-bottom cars comprising a longitudinally-extending shaft mounted opposite the side wall of the car, an arm fast on said shaft, a link pivoted to the free end of said arm, said link having its lower portion formed to hook over and rest upon said shaft when the door is raised, and a chain connecting the lower end of said link with the door, substantially as described.

4. A door-operating mechanism for drop-bottom cars comprising a longitudinally-extending shaft mounted opposite the side wall of the car, an arm fast on said shaft, a link pivoted to the free end of said arm, said link having a curved lower portion adapted to hook over and rest upon said shaft when the door is raised, and a chain connecting the lower end of said link with the outer margin of the door, substantially as described.

5. The combination with a metallic car-body having hinged doors and side posts provided with projecting flanges, of an operat-

ing-shaft rotatably mounted on said flanges, an arm fast on said shaft, a link pivoted to the free end of said arm, said link having a curved lower portion adapted to hook over and rest upon said shaft when the door is raised, and a chain connecting the lower end of said link with the outer margin of the door, substantially as described.

6. A door-operating mechanism for a drop-bottom car having a longitudinal door, comprising a longitudinal shaft, a member connected to and adapted to hook over said shaft when the door is raised, and a chain connecting said member with said door, substantially as described.

7. A door-operating mechanism for a drop-bottom car having a longitudinal door, comprising a longitudinal shaft, a member connected to and adapted to hook over said shaft when the door is raised, and a chain connecting said member with the outer edge of said door, substantially as described.

8. A door-operating mechanism for a drop-bottom car having a longitudinal door, comprising a longitudinal shaft, an arm fast on said shaft, a link pivoted to the free end of said arm, said link having a curved lower portion adapted to hook over and rest upon said shaft when the door is raised, and a chain connecting the lower end of said link with said door, substantially as described.

ETHAN I. DODDS.
